BLAST FURNACE CONSTRUCTION

Wilbur T. Clark, Lakewood, Ohio, assignor of
one-half to Richard W. Treverton, Buffalo, N. Y.

Application March 24, 1939, Serial No. 263,951

8 Claims. (Cl. 266—31)

The present invention relates to blast furnace construction and has particular reference to an improved means for separating solid material from the gas discharged from the furnace, and 5 for re-entering such solid material into the furnace.

In the conventional blast furnace construction, furnace gases are taken from the top of the furnace chamber and carried by downcomers to 10 dust catchers, wherein solid material carried by the gas stream is separated from the gas. Such material, which may vary in size from large pieces to very finely divided particles, may then be transported to a sintering plant to be fused into 15 larger units, after which it may be re-entered into the blast furnace in the usual manner in which the furnace charge is entered.

According to the present invention means for separating solid material from the furnace gas 20 are disposed above the furnace, and the solids recovered are passed, preferably by gravity, into the charging hopper of the furnace.

Means are provided whereby the passage of such material into the charging hopper may be 25 effected at times when the small bell is closed, thereby preventing escape of gas and dust from the dust catchers through the gas seal and small bell opening. Upon filling of the hopper by dropping of the small bell, the returned material 30 is entrapped, and thereafter, upon opening of the large bell, is carried into the furnace chamber with the charge. In this way small particles returned to the furnace chamber may be retained therein, whereas if they were returned directly 35 into the furnace they would be swept immediately into the gas uptakes due to the high gas velocities maintaining in the upper portion of the furnace.

These and other objects and advantages of the 40 present invention will become apparent from the following description of the embodiment of the invention indicated in the accompanying drawing, wherein:

Fig. 1 is a front elevation showing the upper portion of a blast furnace provided with the improved separator and return means;

Fig. 2 is a side elevational view thereof; and,

Fig. 3 is a sectional view taken along line 3—3 of Fig. 1.

As shown in the drawing, the upper portion of 50 the blast furnace 11 may be of usual form, having above the furnace chamber 12 thereof a charging hopper 13 normally closed by a large bell 14, and above hopper 13 a small hopper 15 closed by a small bell 16. A gas seal 29 prevents 55 escape of gas from the furnace when the large

bell is open and supports the small bell hopper 15. Any suitable means, not shown, may be provided to raise and lower the bells whereby the furnace may be charged by opening the small bell to empty the charge from small hopper 15 into the furnace 5 charging hopper 13 while the large bell is closed, and then, while the small bell is closed, dropping the large bell to admit the charge into the chamber 12.

Extending upwardly from the furnace chamber 10 are the usual uptakes 17 through which furnace gases are passed to the conventional downcomers 18. During operation the high velocity of gases passing upwardly through the furnace chamber and through uptakes 17 causes particles 15 of the charge, ranging in size from very finely divided material to relatively large pieces, to be swept from the furnace chamber in the gas stream.

In order to recover and return a large portion 20 of this solid material to the furnace, the present invention provides one or more gas cleaners or separators 19 between uptakes 17 and the downcomers 18, for separating solid material from the gas stream, and conduits 21 extending from the 25 cleaners to the charging hopper 13 for returning the recovered material.

The cleaners 19 may be of any suitable type. In the illustrated embodiment each unit 19 has a cylindrical housing 22 into which a pair of uptakes 17 open as indicated at 23 on opposite sides, and substantially tangentially, to impart a swirling motion to gases entering the housing. A riser 24 opens into the interior of each housing below the inlet openings 23, and terminates at its upper 30 end in a bleeder valve 26. One of the downcomers 18 joins each riser 24 above the housing 22, the juncture being indicated at 25.

The swirling furnace gases passing downwardly in housing 22, and thence upwardly through 40 riser 24, precipitate solid material to the funnel shaped bottom of the housing, from where the material may pass by gravity through the conduits 21 which extend to the large bell chamber, or charging chamber, 13. Valves 27 are provided 45 to control such passage of the recovered solids.

In operation the valves 27 may be normally open to allow passage of solid material from housings 22 but will be closed when the small bell 16 is opened for admitting a charge into chamber 50 13, or prior to such opening. In either case, the material returned through conduits 21, much of which may consist of particles of very small size, will be entrapped in the furnace charge, and will be carried therewith into the furnace chamber- 55

ber 12 upon subsequent opening of the large bell 14. In this way much of the returned material is prevented from being immediately swept again into the uptakes 17 by passing furnace 5 gases.

From the foregoing it will be apparent that the valves 27 may be operated by any suitable means. If desired they may be closed simultaneously with opening of the small bell 15 by having 10 their control levers 28 connected to a cable joining the small bell operating means, or if preferred, they may be operated independently of the small bell. However, the valves 27 should be closed when the small bell 16 is open in order 15 to prevent furnace gases from escaping through small bell hopper to the air.

It will be understood that the structure shown and described herein is merely illustrative of the inventive principle involved, and that these may 20 be otherwise embodied without departing from the spirit or scope of my invention.

I claim:

1. In a blast furnace having a furnace chamber with a gas uptake from the top thereof, a charging hopper above said furnace chamber with a small bell for controlling entrance of a charge thereinto and a large bell for controlling passage of said charge therefrom into the furnace chamber, a separator associated with said gas 25 uptake for separating solid material from the gas, a conduit for passing such solid material from the separator into the charging chamber, and valve means associated with said conduit for the controlling passage of material therethrough, 30 whereby such passage may be effected at times when said small bell is in closed position.

2. In a blast furnace having a furnace chamber, a charging hopper thereabove with a small bell for controlling entrance of a charge there- 40 into and a large bell for controlling the movement of the charge from said hopper into the furnace chamber, means for conducting gas from the furnace chamber and means associated therewith for separating solid material from the gas, 45 and means for conducting such solid material into said hopper, said means including a valve whereby such solid material may be entered into said hopper at times when said small bell is closed.

3. In a blast furnace having a furnace chamber, a charging hopper thereabove with a small bell for controlling entrance of a charge there- 50 into and a large bell for controlling the movement of the charge from said hopper into the furnace chamber, means for conducting gas from the furnace chamber and means associated therewith for separating solid material from the gas,

and valved passage means for passing such solid material into said hopper.

4. In a blast furnace having a charging hopper provided with a valve for admitting a charge into said hopper, and the furnace having a gas 5 uptake, a cylindrical housing above the charging hopper, said gas uptake opening into the housing substantially tangentially thereof, a gas outlet pipe extending from said housing and having its inlet end in said housing below the opening 10 of said gas uptake, and a conduit extending from the bottom of said housing into said charging hopper.

5. In a blast furnace having a charging hopper provided with a valve for admitting a charge 15 into said hopper, and the furnace having a gas uptake, a cylindrical housing above the charging hopper, said gas uptake opening into the housing substantially tangentially thereof, a gas outlet pipe extending from said housing, and a conduit 20 extending from the bottom of said housing into said charging hopper.

6. In a blast furnace having a furnace chamber and a charging hopper thereabove provided with a valve for admitting a charge into said 25 hopper, a substantially cylindrical housing above said hopper, a gas uptake from said furnace chamber opening into said housing substantially tangentially thereof, a gas outlet from said housing, a conduit extending from the bottom of said 30 housing to said hopper for passing into the latter solid material which has been precipitated from the gas to the bottom of the housing, and a valve in said conduit for opening or closing the latter to such passage.

7. In a blast furnace having a charging hopper provided with a valve for admitting a charge into said hopper, and the furnace having a gas uptake, a separator associated with the gas uptake for separating solid material from the gas, 40 means for passing such solid material from the separator into said hopper, and valve means associated with the last mentioned means for controlling the passage of such solid material into said hopper.

8. In a blast furnace having a furnace chamber, a charging hopper thereabove with a small bell for controlling entrance of a charge there- 50 into and a large bell for controlling movement of the charge from said hopper into the furnace chamber, means for conducting gas from the furnace chamber including means for separating solid material from the gas, and a conduit for passing such solid material into said hopper, said conduit having associated therewith means 55 whereby the conduit may be closed while the small bell is open.

WILBUR T. CLARK.
